United States Patent Office.

HERRMANN AHREND, OF NEW YORK, N. Y.

Letters Patent No. 85,776, dated January 12, 1869.

IMPROVEMENT IN DOOR-LOCKS.

The Schedule referred to in these Letters Patent and making part of the same.

To all whom it may concern:

Be it known that I, HERRMANN AHREND, of the city, county, and State of New York, have invented a new and useful Improvement in Locks; and I do hereby declare the following to be a full, clear, and exact description thereof, which will enable those skilled in the art to make and use the same, reference being had to the accompanying drawing, forming part of this specification, in which drawing—

Figure 1 represents a longitudinal section of this invention.

Figure 2 is a plan thereof when the back plate is removed.

Figure 3 is a detached section of the unlocking-mechanism.

Similar letters indicate corresponding parts.

This invention relates to a lock in which the bolt is thrown out by the action of a ring or handle, which is hinged to standards rising from the lock-plate, and which is provided with a toe that acts on a projection rising from the shank of the bolt in such a manner that when the bolt is pushed back, and, consequently, the lock is open, the ring or handle is thrown out in the proper position to open the drawer, door, or other article to which the lock is attached, and when the ring or handle is turned down, the bolt is thrown out, and the drawer, door, or other article becomes locked.

When the bolt is out in its locking-position, it is retained by a spring-catch, which is disengaged by the action of a key on a wedge, and on two levers, the ends of which are situated over a notched stud, and project over the end of a spring-catch in such a manner that if a key of the proper shape is applied, the wedge carries the levers directly over the notches in the stud, and as the key is still further depressed, the levers enter said notches and cause the spring-catch to release the bolt, allowing the same to follow the action of a spring, which carries it back to its original position.

A represents a plate or case, which supports the mechanism of my lock.

On this plate rests the bolt B, which is exposed to the action of a spring, C, that serves to carry said bolt back to the position which it occupies in figs. 1 and 2 of the drawing.

The inner end of the shank of the bolt is guided between two standards a, which rise from the plate A, and these standards form the bearings for the fulcrum-pin b of the ring or handle D.

From this ring projects a toe, c, which acts on a projection, d, rising from the shank of the bolt, as shown in fig. 1.

When the ring or handle D is turned down in the direction of the arrow marked near it in fig. 1, the bolt is thrown out in its locking-position, and in this position it is retained by a spring-catch, e, which catches in a recess, f, at the inner edge of the shank of the bolt.

When the spring-catch is thrown out of the recess f, the bolt is released, and it is carried back to its original position by the action of the spring C.

When the bolt is in this position, the ring or handle D occupies the position shown in fig. 1, and the door, drawer, or other article to which the lock is attached, can be opened with ease and facility.

When the bolt is thrown out and retained by the spring-catch e, the handle or ring D can be turned down out of the way, or it can be turned out to the position shown in fig. 1, as may be desirable.

The spring-catch e is released by the action of a key, K, (see fig. 3,) which is introduced through a tube, g, projecting from the back plate of the lock, as shown in fig. 1.

This key consists of a simple piece of sheet-metal, one end of which is provided with a notch, h, and two prongs, i i, (see fig. 3,) and as the key is pushed down through the tube g, the prongs straddle a wedge, j, which is situated over two spring-levers, k k.

The ends of these levers project over the end of the spring-catch e, and also over a stud, l, which is provided with two notches, m.

If the proper key is used, the wedge j forces the levers k apart just far enough to carry them over the notches m, and then the prongs i bearing on the levers depress them into the notches m, and cause them to act on the spring-catch e, thereby releasing the same.

If the notch h and prongs i i of the key are not exactly of the required shape, the levers k k are either pressed apart too far, or not far enough, so that they cannot enter the notches m, and unless they can enter these notches they do not act on the spring-catch e, and the bolt remains locked.

By these means, a lock is obtained which is very simple in its construction and operation, which requires but a very small key, and which can only be picked with the greatest difficulty.

If my lock is to be used for doors on rooms or houses, an additional ring or handle can be attached to its opposite side, which can also be made to act on the bolt the same as the ring D.

Having thus described my invention,

What I claim as new, and desire to secure by Letters Patent, is—

1. The construction and arrangement of the bolt B, f, d, ring D, having toe c, spring C, and spring-catch e, all combined and operating in the manner described, whereby, when the catch e is released from notch f, the bolt B is thrown entirely inward and unlocked by the spring C, as set forth.

2. The wedge j and levers k k, in combination with the notched stud l, spring-catch e, and bolt B, substantially as and for the purpose described.

HERRMANN AHREND.
